UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

SPRING PLANK FOR RAILWAY-CAR TRUCKS.

Application filed September 7, 1923. Serial No. 661,470.

To all whom it may concern:

Be it known that I, BYERS W. KADEL, a citizen of the United States, residing at Baltimore, in the State of Maryland, have 5 invented certain new and useful Improvements in Spring Planks for Railway-Car Trucks; and I do hereby declare the following to be a full, clear, and exact description of the invention, such as will enable others 10 skilled in the art to which it appertains to make and use the same.

My invention relates to spring planks for railway car trucks, and more particularly to an improved construction of spring plank 15 seat member adapted for use on wrought metal side frames.

One of the principal features of the invention is to provide a spring plank seat member having longitudinally extending depending portions designed to engage neighboring portions of the side frame adjacent the lower portion of the bolster opening, and upright portions disposed transversely of said depending portions and connected thereto, said upright portions being adapted to bridge the longitudinally extending portions for distributing the load transversely of the side frame to the depending portions, which latter act to transmit the load 20 longitudinally of the side frame.

Another object of the invention consists in constructing a spring plank seat member with vertically disposed transversely extending ribs or flanges, said ribs being arranged 25 at opposite ends of the seat member and shaped to receive a spring plank of channel cross section to which they are connected, said construction adapting a wrought metal side frame for use with a spring plank designed to receive a plurality of advantageously disposed bolster springs.

A further object of the invention involves the production of a strong construction of spring plank seat member having a body portion adapted to rest upon the beam member of the side frame the full distance of the bolster opening longitudinally of the side frame, said body portion having its opposite ends shaped to conform to the corner 30 portions of the bolster openings at the junction of the truck column with the beam member, the upstanding ribs of the seat member intersecting said body portion near the ends thereof and being continued upon 35 each side of the bolster opening a distance

substantially corresponding to the lateral extensions of the body portion disposed upon each side of the bolster opening.

A still further object of the invention is to provide a reliable spring plank construction involving a saddle casting having a spring plank connected thereto, a portion of the means connecting the spring plank to said casting being advantageously disposed adjacent the spring seating surface of 40 the plank and adapted to retain the bolster springs in their respective positions.

A still further object of the invention consists in providing a strong but comparatively light weight spring plank seat member in which the associated longitudinal and transverse ribs are effectively reinforced by a plurality of advantageously arranged flanges, the relation of the several ribs and flanges providing for uniform distribution 45 of the loads to the side frame and more especially those portions neighboring the seat casting.

The invention further resides in the construction, combination and arrangement of 50 the several parts to be hereinafter referred to and pointed out in the claims.

In the drawings illustrating two embodiments of my invention as applied to a wrought metal car truck side frame,—

Figure 1 is a fragmentary view of a wrought metal car truck side frame showing my improved spring plank construction applied thereto.

Figure 2 is a horizontal sectional view 60 through the side frame shown in Fig. 1, illustrating the spring plank construction in plan view.

Figure 3 is a view in end elevation of the spring plank seat member and spring plank 65 connected thereto, the adjacent portion of the side frame being shown in transverse section.

Figure 4 is a vertical longitudinal sectional view on the line 4—4 of Fig. 2.

Figure 5 is a transverse vertical sectional view on the line 5—5 of Fig. 2.

Figure 6 is a fragmentary view of a wrought metal side frame illustrating a modified construction of spring plank seat 70 member and spring plank applied thereto.

Figure 7 is a horizontal sectional view through the side frame illustrating in plan view the modified construction shown in Fig. 6.

Figure 8 is a view in end elevation of the modified construction of spring plank seat member, the adjacent portion of the side frame being shown in transverse section.

6 Figure 9 is a vertical longitudinal sectional view on the line 9—9 of Fig. 7.

Figure 10 is a transverse vertical sectional view on the line 10—10 of Fig. 7.

10 Figure 11 is a detail sectional view on the line 11—11 of Fig. 7.

Referring to the drawings, in which similar reference characters designate corresponding parts in the several views, and particularly to Figs. 1 to 5, inclusive, my improved spring plank construction is shown applied to a wrought metal side frame having an inner wall 1 and an outer wall 2, each of said walls being preferably formed with top arch bar portions providing the compression member (not shown), bottom arch bar portions forming the tension member, and particularly the beam portion 3 thereof, and truck column portions 4 uniting said compression and tension members of the truck. In the present construction of side frame the sides of the truck column portions adjacent the bolster opening are bordered by stiffening flanges 5. The column stiffening flanges are designed to merge into flanges 6 which border the lower end of the bolster opening, said flanges in addition to stiffening the inner and outer walls being also designed to provide a spring plank seat adapted to receive the seat portion of the spring plank. The truck column stiffening flanges merge into the corresponding stiffening flanges at the base of the bolster opening through a suitable curving of the flanges at their respective points of junction, portions 40 of the spring plank construction being designed to coact with these curved corner portions in establishing a rigid connection between the spring plank and side frame whereby the loads are effectively transmitted 45 to portions of said frame which are best able to receive them.

The spring plank is formed of a structural channel the web 7 thereof at each end providing a relatively wide and flat connecting portion between the flanged sides 8 upon which the bolster springs are positioned. The flanges 8 of the spring plank project upwardly from the seat portion 7 at right angles thereto and in relative close proximity to the truck columns, said flanges being relatively thickened at their junctions with the web and providing a strong transverse construction the loads from which must be properly distributed to the side frame whereby the critical points of the frame will not be subjected to damaging strains resulting in failure of the side frame.

The means by which the transverse loads are distributed to the side frame involves a spring plank seat member 9 having an upper

seat portion adapted to receive the spring plank and an under portion designed to rest upon the beam member of the frame and embrace the oppositely disposed side walls of the side frame with portions of said seat member contacting the lower corner bends of the bolster opening.

The seat member or saddle casting is provided with longitudinally extending depending ribs or flanges 10, said flanges being disposed to embrace the neighboring portions of the side frame adjacent the bolster opening and acting to resist any spreading or separation of the walls of the side frame at this point. The ribs 10 are arranged in spaced parallel relation and preferably extend substantially the full length of the bolster opening, said ribs being adapted to distribute the strains longitudinally of the side frame after receiving them from the transverse rib portions projecting from the body portion of the seat member.

The transverse portions of the seat member involve upright ribs or flanges 11 arranged at the respective ends thereof, the spring plank being fitted between said ribs and having its flanged sides secured against the inner faces of said ribs by rivets 12, said connection providing a rigid construction whereby the transverse loads are first received by said ribs and then redistributed longitudinally of the side frame. The transverse ribs are designed to project beyond the opposite side walls, said projecting portions being suitably braced by reinforcing flanges 100 and designed to receive the rivets 12, the inner heads of which are preferably flattened as shown to provide for the introduction of the bolster springs. The projecting portions of the transverse ribs extend beneath the 105 spring plank and are united to the longitudinally disposed ribs 10.

Each transverse vertical rib 11 is reinforced by vertical longitudinally disposed angular flanges 13, said reinforcing flanges 110 preferably constituting continuations of the depending ribs 10 in an upward direction at each end of the seat member. Horizontally disposed reinforcing angular flanges 14 are also provided, said flanges lying preferably 115 in the same horizontal plane as the body portion of the seat member and serving to embrace the casting at the intersection of the longitudinal and transverse ribs.

The respective ends of the seat member and particularly that portion lying between the reinforcing flanges 13 are each relatively thickened and shaped both longitudinally and laterally to conform to the contour 120 of the adjacent corner bends of the bolster opening at the junctions of the beam member and truck columns. This construction assures a rigid connection between the spring plank and side frame whereby the transverse and longitudinal loads are uni- 130

formly distributed at the critical points in the side frame and absorbed by the side frame without distortion of the side walls or side frame portions provided therein.

- 5 The body portion of the spring plank seat member is extended laterally upon each side of the bolster opening, the spring plank being connected to said extensions by means of rivets 15 the upper heads of which are 70
10 countersunk to provide smooth seating surfaces for the springs. One of the rivets 16 connecting the spring plank to the relatively larger inner extension of the seat member is formed with its head portion projecting 75
15 upwardly to provide bolster spring retaining means, the bounding edges of the springs being indicated by dot and dash lines in Fig. 2.

The outer edge of the seat member is provided with a flange 17, said flange being of a height corresponding to the thickness of the web 7 of the spring plank, whereby it affords a spring seating surface flush with the seating surface of the spring plank. The 80
20 inner portion of the flange 17 is preferably enlarged to receive portions of adjacent bolster springs, as indicated by the dot and dash lines in Fig. 2, said portion being interrupted, however, with a vertically projecting lug 18 disposed in transverse alignment with the rivet head 16 and having its inner face curved to conform to adjacent curved portions of the springs. A convenient and very reliable mounting of the 85
25 bolster springs is provided as the result of this combination, a particular style and arrangement of standard A. R. A. spring being used in the foregoing embodiment of the invention. The flanged edge 17 is preferably braced at each end by angular flanges 19, said flanges being united to the laterally projecting ends of the transverse ribs 11.

Reinforcing angular flanges 20 are provided for the lateral extensions of the body 90
45 portions of the seat member, said flanges paralleling the transverse ribs 11 and being located therebetween. It will be observed that the seat member is grooved transversely 100
50 thereof at the junction of the inner faces of the transverse ribs with the adjacent upper seating surface, thereby permitting a full right angular disposition of the metal in the spring plank at this juncture point 105
55 with correspondingly increased strength value.

In the modified construction of my invention shown in Figs. 6 to 11, inclusive, the 110
60 pressed metal spring plank 21 is provided with relatively wide end portions forming spring seating surfaces, the flanged sides of the plank being offset adjacent said end portions and extending through the bolster opening in close proximity to the truck 115
65 columns. The spring plank seat member 22

is interposed between the spring plank and side frame, the upper surface of the seat member being shaped to receive the spring plank 21, and the under face thereof being designed to rest upon the beam portion of 70
75 said frame and conform to the contour of the corners of the bolster opening at the junctions of the truck columns with said beam portion.

The side frame to which the seat casting 75
80 is shown applied is of the wrought metal type, the mergence of the truck column stiffening flanges 5 into the corresponding stiffening flanges 6 at the base of the bolster opening being effected through gradual curving of the flanges at their respective points of juncture, the radius of curvature of the merging stiffening flanges being greater than the radius of curvature of the 85
90 spring plank at the junction of the spring seating surface thereof with the side flanges of the plank, as clearly shown in Figs. 9 and 11. The lower face of the spring plank seat member is formed with corresponding gradual curves at its opposite ends, but the upper surface of said seat member adjacent said ends is differently shaped and curved to receive the spring plank, the curvature of which latter is designed to provide adequate clearance between the side edges 95
95 of the spring plank and truck columns. The construction of spring plank and seat member lends itself very well in permitting the metal of the beam portion of the side frame to be increased in depth and consequent 100
105 strength value without reducing the clearance between the bottom of the side frame and the top of the rail, the increase in metal at these critical points offering great resistance to the strains incident to service 110
115 conditions. A corresponding increase in strength is therefore given the beam member when the bolster opening is designed to receive the bolster springs in the arrangement shown in dot and dash lines in Fig. 7.

The spring plank seat member or saddle casting 22 comprises a body portion having depending longitudinally disposed ribs or flanges 23 adapted to embrace neighboring portions of the side walls of the side frame, the under face of said body portion between said flanges being provided with a plurality of longitudinally and transversely disposed intersecting ribs 24 designed to rest upon the beam portion. The transversely arranged ribs 24 are preferably interrupted centrally of the seat member as at 25 to provide ample space for the weld or rivet connections used in uniting the inturned stiffening flanges of the bottom arch bar 120
125 portions forming the beam member. The ribbed under face of the seat member provides for a very strong but comparatively light weight casting capable of sustaining the loads and preventing separation of the 130

side frame walls at this point of the side frame.

Upstanding transversely disposed ribs or flanges 26 are provided near each end of the 5 seat member, said ribs acting to distribute the transverse loads to the longitudinally extending ribs or flanges 23 through the body portion of the casting. The end portions of the transverse ribs project beyond 10 the bolster opening upon each end thereof and are connected to the flanged sides of the spring plank by rivets 27. Intermediate portions of each transverse rib may be cut away as indicated at 28 for purposes of 15 lightening the casting without sacrificing its strength value. The transverse ribs between the depending flanges 23 are merged into the body portion of the seat member with their upper and lower surfaces differently curved corresponding to the adjacent curved surfaces of the spring plank and side frame portions at the lower corners of the bolster opening. Beyond the 20 depending flanges the emergence of the transverse ribs and lateral extensions of the seat member is preferably effected through a uniform curving of the respective upper and lower faces as illustrated in Fig. 6. Each transverse rib is preferably braced 25 by metal flanges 29, said flanges being disposed in longitudinal alinement with the depending flanges 23 of which they form continuations at each end of the seat member.

The opposite end portions of the casting 30 are preferably thickened as at 30, said portions serving to rigidly position the seat member between the truck columns and uniformly impart the loads longitudinally of the side frame. The interrupted portions 35 of the ribbed under face are continued through the said thickened ends to permit of the weld or rivet connection being continued around the lower corners of the bolster opening. The end portions of the depending 40 flanges 23 are preferably enlarged as shown in Fig. 6, this increase in metal acting to resist the forces developed at the ends of the seat member incident to the squaring action of the truck. A plurality of reinforcing flanges 31 are also provided between the 45 respective end portions for integrally uniting the depending flanges with the lateral extension of the body portion of the seat member.

50 The spring plank is adapted to be connected to the lateral extension of the seat member by a plurality of rivets 32, the innermost rivets having their heads projecting above the spring seating surface to form a spring retaining means. The outer rivets are designed to pass through a raised portion 55 of the spring plank, said portion being disposed in alinement with the heads of the inner rivets longitudinally and centrally of the spring plank and being curved

to conform to the bounding edge portions of the bolster springs whereby they are retained in position upon the spring plank. The outer rivets are connected to the adjacent lateral extension of the seat member, 70 which extension, along the outer edge and adjacent that portion receiving said rivets, may be cut away as at 34 between the adjacent reinforcing flanges 31.

75 Filling washers 35 are preferably inserted between the raised portions 33 of the spring plank and the upper face of the seat member.

The seat member 22 is formed with an upstanding annular rib 36 adapted to form 80 a pivot boss for the spring plank which is provided with an opening 37 into which the annular rib projects. This construction permits of a connection between the spring plank and side frame in the use of which 85 the rivets rigidly connecting the spring plank to the seat member may be omitted.

90 A spring plank construction designed in accordance with my present invention provides for an even distribution of the loads to the side frame, and particularly the lateral forces exerted in the truck as the result of service conditions. It will be observed that the spring plank seat members disclosed in the present embodiments of the invention can be economically manufactured and advantageously connected to the spring plank in such a manner as to prevent displacement of the bolster springs.

95 It will be understood that various other embodiments of spring plank and spring plank seat can be produced, and I do not wish to be understood as limiting the invention to the disclosures herein.

100 I claim:—

105 1. The combination with a car truck side frame, of a spring plank and a seat member having a body portion providing a seating surface for said plank, said body portion being formed with longitudinally disposed ribs arranged to embrace the side frame and upstanding transversely disposed ribs bridging the longitudinal ribs and connected to the spring plank.

110 2. The combination with a car truck side frame, of a spring plank and a seat member having a body portion providing a seating surface for said plank, said body portion having depending longitudinally disposed flanges embracing neighboring portions of the side frame and vertically disposed transversely extending flanges bridging said depending flanges, said vertical flanges being connected to the spring plank and designed to impart the transverse loads 115 the full width of said seat member.

120 3. The combination with a car truck side frame of a plank, and a seat member having a body portion providing a seating surface for said plank, said body portion having a 125

plurality of vertically disposed intersecting flanges, said flanges extending substantially the width and length of the seat member and being adapted to transfer the transverse 5 loads longitudinally of the side frame.

4. The combination with a railway car truck of oppositely disposed side frames, and means including a spring plank rigidly connecting said side frames, said means involving longitudinally and transversely extending upright ribs provided on said spring 10 plank, some of said ribs being adapted to embrace adjacent portions of the side frame and other of said ribs being arranged to bridge the ribs embracing the side frame for transferring the transverse loads of the truck longitudinally of the side frame.

5. The combination with a car truck side frame having truck columns and a bolster opening, of a spring plank extending into said opening and a seat member providing a seating surface for said plank, said seat member having end portions contacting neighboring portions of the side frame adjacent the lower ends of the truck columns and a plurality of longitudinally and transversely extending ribs, said ribs intersecting each other adjacent the end portions of the seat member.

30 6. The combination with a car truck side frame having truck columns and a bolster opening, of a spring plank having a relatively wide spring supporting surface extending into said opening, and a spring 35 plank seat member formed with a seating surface for the spring plank extending substantially the full length of the bolster opening, said seat member being provided with longitudinally extending ribs embracing neighboring portions of the side frame throughout the length of the seat member and transversely disposed ribs bridging said longitudinal ribs in close proximity to the truck columns, said transverse ribs 40 acting to transfer the transverse loads longitudinally of the side frame.

45 7. The combination with a car truck side frame, of a spring plank, and a spring plank seat member having a surface adapted to receive said plank, said seat member being provided with an upstanding transversely arranged rib adjacent each end thereof and extending substantially the full width of the seat member, and longitudinally extending 50 ribs intersecting said transverse ribs and arranged to embrace neighboring portions of the side frame.

8. The combination with a car truck side frame, of a spring plank, and a spring plank seat member having a surface adapted to receive said plank, said seat member being provided with transversely extending ribs 55 projecting upon each side of the side frame and connected to the spring plank, and longitudinally extending ribs intersecting said

transverse ribs and adapted to embrace neighboring portions of the side frame.

9. The combination with a car truck side frame, of a spring plank, and a spring plank seat member having a surface adapted to receive said plank, said seat member being provided with depending longitudinally extending ribs arranged to embrace neighboring portions of the side frame, and upstanding transversely disposed ribs bridging the 75 longitudinal ribs, said transverse ribs being adapted to project beyond said longitudinal ribs and be connected to the spring plank, and reinforcing flanges for said longitudinal and transverse ribs adjacent their intersection.

10. The combination with a car truck side frame having a bolster opening, of a spring plank extending into said opening, and a spring plank seat member provided with depending longitudinal flanges adapted to engage adjacent portions of the side frame, said seat member having transversely disposed upstanding flanges bridging said depending flanges, said seat member being provided with laterally extending portions upon each side of the bolster opening, said laterally extending portions serving to unite the intersecting transverse and longitudinal flanges and providing a seating surface of 95 relatively large area for a spring plank.

11. The combination with a car truck side frame having a bolster opening, of a spring plank extending into said opening and a seat member provided with depending vertically 100 disposed ribs adapted to embrace adjacent portions of the side frame and transversely disposed upstanding ribs bridging said depending ribs, the end portions of said transverse ribs extending beyond the depending 105 ribs, said seat member being formed with laterally extending portions adapted to unite the longitudinal and transverse ribs upon each side of the bolster opening, and means connecting said transverse ribs and laterally extending portions to the spring 110 plank.

12. The combination with a car truck side frame having a bolster opening, of a spring plank extending into said opening and a seat member provided with depending vertically 115 disposed ribs adapted to embrace adjacent portions of the side frame and transversely disposed upstanding ribs bridging said depending ribs, the end portions of said transverse ribs extending beyond the depending ribs, said seat member being formed with laterally extending portions adapted to unite the longitudinal and transverse ribs upon each side of the bolster opening, and means including rivets connecting the spring plank to said transverse ribs and laterally extending portions, at least one of the rivets providing a projection for preventing the displacement of the bolster springs.

13. The combination with a car truck side frame having truck columns and a bolster opening, of a spring plank extending into said opening and having its side edges disposed in relatively close proximity to said truck columns, and a spring plank seat member having depending portions adapted to embrace neighboring portions of the side frame, said seat member being provided with upstanding transversely disposed portions connected to said depending portions and to the sides of said spring plank.
14. The combination with a wrought metal car truck side frame having a bolster opening, of a spring plank extending into said opening, and means connecting said spring plank to the side frame for uniformly distributing the loads thereto, said means comprising a spring plank seat member having longitudinally extending ribs adapted to engage adjacent portions of the side frame and transversely extending ribs connected to said longitudinally extending ribs and to the spring plank.
15. A spring plank construction involving a channel spring plank and seat member, said seat member having longitudinally disposed flanges and transversely disposed flanges, said transverse flanges bridging and intersecting said longitudinal flanges adjacent the ends of the seat member, and means connecting said transverse flanges to the flanges of the channel spring plank at points outside of the longitudinal flanges.
16. A spring plank seat member comprising a body portion forming a relatively large seating area, longitudinally disposed flanges depending from said body portion, transversely arranged flanges projecting upwardly from said body portion, and reinforcing angular flanges for said transverse flanges at each end of the seat member, said reinforcing flanges being arranged in alignment with the body portion and depending flanges, respectively, of the seat member.
17. In combination, a car truck side frame having inner and outer walls arranged in spaced relation, each of said walls having a plurality of truck column portions and bottom arch bar portions, stiffening flanges bordering said side wall portions, a spring plank having a portion adapted to rest on the stiffening flanges bordering the bottom arch bar portions and contact said flanges at their junctions with the flanges of the

truck column portions, and means including vertically disposed intersecting ribs provided on said spring plank, some of said ribs being adapted to embrace the side walls longitudinally of the side frame, and other of said ribs uniting said longitudinal ribs and being arranged at an angle thereto for receiving the transverse forces imparted to the side frame.

18. In combination, a car truck side frame provided with a bolster opening, the metal of the side frame at the bottom of said opening being of varying cross sectional area, a spring plank extending into said bolster opening, and a spring plank seat member having longitudinal ribs embracing adjacent portions of the side frame, said seat member having portions of relative reduced thickness designed to compensate for the varying increase in cross sectional area of the metal beneath the bolster opening, said seat member being provided with upstanding transverse ribs disposed in close proximity to the reduced portions of the seat member, said transverse ribs being adapted to bridge the longitudinally disposed ribs and having portions connected to the spring plank.

19. A spring plank seat member for wrought metal side frames comprising a body portion having each end formed with differently curved upper and lower faces, said curved faces permitting a maximum depth of metal in the beam portion of the side frame uniting the truck columns while maintaining the depth of the bolster opening and rail clearance beneath the beam member constant, said body portion being provided with a plurality of intersecting ribs some of which are adapted to embrace the side frame and others of which project from the upper curved surface of the seat member adjacent each end thereof.

20. The combination with a car truck side frame, of a spring plank and a seat member having a body portion providing a seating surface for said plank, said body portion being formed with longitudinally disposed ribs arranged to embrace the side frame and upstanding transversely disposed ribs bridging the longitudinal ribs and embracing the spring plank.

In testimony whereof I affix my signature.

BYERS W. KADEL.
